FUEL INJECTION PUMP

George P. Lum, South Bend, Ind., assignor to
Bendix Aviation Corporation, South Bend,
Ind., a corporation of Delaware

Application August 5, 1943, Serial No. 497,529

11 Claims. (Cl. 103—41)

This invention relates in its broader aspect to means for effecting fine adjustments in mechanical devices, and is particularly shown and described herein, by way of example, as applied to mechanisms for adjusting the effective pumping stroke of plungers or pistons of fuel injection pumps.

As is well known in the art, it is highly desirable to have extreme accuracy in the metering of the fuel delivered by fuel injection pumps to the end that the quantities of fuel delivered by the individual plungers of the pump should be as nearly equal as possible. It is also important in pumps of this character to time the delivery of the fuel with extreme accuracy, both as to the commencement of the delivery stroke and as to the ending thereof, but even with careful precision manufacturing methods it has been found in practice that there are unavoidable variations in the diameters of the various plungers or pistons, the spacing of the cut-off annuli and fuel ports, et cetera. These variations result in a delivery of unequal quantities of fuel from the individual pump plungers which causes uneven operation of the engine, a loss in maximum available power, and a decrease in engine performance and economy. Various means have been proposed heretofore to adjust the effective fuel delivery stroke of the various plungers of fuel injection pumps to compensate for the aforementioned manufacturing variations, but these have not proven entirely satisfactory for various reasons.

It is therefore an important object of the present invention to provide means for adjusting the effective stroke of the plungers of fuel injection pumps with extreme accuracy to compensate for various inaccuracies in the manufacture of the pump, plungers and operatively associated parts which adversely affect the uniformity in the fuel delivery from the individual plungers of the pump.

Another object of the invention is to provide means for effecting a fine longitudinal adjustment which may be particularly useful in connection with sleeve assemblies for fuel pumps of the above type but which is capable of general application in arrangements wherein a fine longitudinal adjustment is required between adjacent or cooperating parts.

It is another object of the invention to provide an arrangement of this character having simple and effective locking means for retaining the assembly in adjusted positions, said lock-

ing means being readily releasable for making adjustments.

Still another object of the invention is to provide novel means for making various extremely accurate adjustments between parts of a mechanism.

The characteristics and advantages of the invention are further sufficiently referred to in connection with the following detailed description of the accompanying drawing, which represents a preferred embodiment of said invention. After considering this example, skilled persons will understand that the adjustable mechanism here disclosed is suitable to many uses, and that many variations may be made without departing from the principles disclosed; and I contemplate the employment of any structures, arrangements, or modes of operation, that are properly within the scope of the appended claims.

20 In the drawing:

Figure 1 is a sectional view of a fuel injection pump embodying the present invention;

Figure 2 is a longitudinal section of the adjustable by-pass sleeve assembly; and

25 Figure 3 is an isometric exploded view of the parts of the by-pass sleeve assembly.

Referring more particularly to the fuel injection pump shown in Figure 1, said pump includes a main drive shaft 10 which drives a member 12 through an Oldham type universal coupling of known construction, indicated at 14. A locating pin 16 is provided to prevent incorrect assembly of the coupling which would change the timing of the injection pump relative to the engine. A wobble plate 18, mounted on the member 12, is slidably engaged by a plurality of tappets 20 reciprocably mounted in bushings 22 uniformly spaced around the periphery of the injection pump. Pump plungers 24 are coaxially arranged relative to the tappets 20 and are slidably received in bushings 26 which form the individual pump cylinders. In view of the fact that each of the tappet and plunger assemblies and the control mechanism therefor are all alike,

30 40 45 the following detailed description will be directed to the upper plunger and tappet. A spring 28 cooperates with a washer supported on a horseshoe or split retainer 29 received in a groove in the plunger 24 and urges the plunger to the left, maintaining the plunger and tappet in constant contact with each other and maintaining the tappet against the wobble plate 18. The plunger and tappet are preferably made as separate abutting pieces rather than as one piece,

50 55 so that minor variations in alignment of the

bushings 22 and 26 may be accommodated without tending to bind the assembly. A spring 30 is provided to move the tappet out of engagement with the wobble plate in the event the plunger 24 becomes stuck. The pumping plunger 24 is provided with a central bore 32 in communication with a pair of spaced annuli 34 and 36.

An externally threaded by-pass sleeve or member 38, best shown in Figures 2 and 3, is slidably mounted on the plunger 24 and includes an outwardly extending flange 40 having a plurality of notches 42 equally spaced about the periphery thereof. Threadably received on the sleeve is a member 44 which is carried by a plate 46, the latter being provided circumferentially with spaced apart notches adapted to be snugly received in a grooved portion 48 of the member 44. The plunger 24 prevents the assembled sleeve 38 and member 44 from sliding out of the cooperating notch and the sides of the groove 48 prevent longitudinal movement of the member 44 relative to the plate 46. Although the width of the groove 48 is such that there is no longitudinal movement of the member 44 relative to the plate said member is free to rotate within the notch of the plate, it being considered desirable to allow such rotation. The end of the member 44 adjacent the flange 40 of sleeve 38 is provided with an annular coaxial recess 50 and an annular flange-like wall 51 projecting toward the flange 40, the wall 51 being provided with a plurality of notches 52 equally spaced circumferentially of said flange. In the form illustrated the flange 40 is provided with one more notches than is the wall 51, however the number of notches on the wall and flange may be varied to obtain any desired fineness of adjustment. Means for locking the sleeve in adjusted positions comprises a spring 54 carried by and disposed about the sleeve 38 and the adjacent end portion 56 of the grooved member 44. This spring is provided with a bent end section 58 the free end of which is adapted to be selectively received in notches 42 of the flange 40 and a curved portion 60 at the other end of said section 58 is arranged to selectively engage notches 52 of the member 44, it being understood that with the parts in assembled relation the spring expands and one end thereof fits within the recess 50, see Figure 2. If desired the pump may be provided with removable plugs 61 positioned adjacent the respective sleeve assemblies to permit adjustments of said sleeves, in a manner to be hereinafter described, without disassembling the pump.

The plate 46 is secured to a slidably mounted piston 62 which is urged to the right by a spring 64 and is moved to the left against the spring by a rod 66 pivotally connected to one end of a lever 68 having its other end pivotally connected to a link 70 secured to a diaphragm 72 which forms a movable wall between the interior of the pump and a chamber 74 which may be connected to a venturi in the induction passage of a charge forming device, not shown, by means of a passage 76. The effective fuel delivery of the pump is varied by variations in pressure on diaphragm 72 as fully explained in the copending Evans application for a Charge forming device, Serial No. 475,783, filed February 13, 1943. The left end of rod 66 is of a rounded conical shape and is abuttingly received in a rounded conical depression in a member 78 secured to the piston 62. This construction facilitates assembly and permits the necessary slight rocking movement of rod 66 upon movement of lever 68. The interior of the housing of the pump forms a fuel reservoir 80 which

receives fuel from a suitable source through a conduit 82.

The operation of the pump shown in Figure 1 is as follows, starting with the upper plunger in its extreme right-hand position corresponding to the end of the stroke: Upon rotation of the wobble plate 18, the plunger 24 will move to the left until the annulus 34 passes to the left of the by-pass sleeve 38. At this time, fuel enters through the annulus 34 and bore 32 to fill the pumping space to the right of the end of plunger 24. Upon movement of the plunger to the right, fuel will be pumped back out of the annulus 34 until it passes into lapped relation with by-pass sleeve 38 which determines the beginning of injection. Further movement of the plunger forces the trapped fuel past a spring loaded check valve 84 into a passage 86, thence to a nozzle supply pipe and nozzle, not shown, which discharges the fuel under high pressure into the engine cylinder. Fuel is discharged from the nozzle until the annulus 36 passes into registry with an annulus 88 vented to the reservoir 80, whereupon the remaining fuel in the cylinder of plunger 24 is pumped into the reservoir 80. This arrangement suddenly relieves the pressure of the fuel being pumped and quickly cuts off injection, thereby eliminating dripping at the nozzle. Preferably the annulus 36 and the annulus 88 are brought into registry shortly before the end of the stroke of plunger 24 so that the latter portion of the stroke, which is at a rapidly decreasing plunger velocity which would produce a decreasing fuel injection pressure, will not be utilized for injecting fuel into the engine. This confines the injection period to the relatively high velocity period of the plunger and the resulting high injection pressure period, whereby better atomization at the nozzle is obtained.

Movement of the by-pass sleeve 38 to the right increases the portion of the stroke during which the annulus 34 is open to the reservoir, or in other words delays the beginning of injection, and consequently reduces the effective stroke of the plunger. If the by-pass sleeve 38 is moved to its extreme right-hand position, the annulus 34 does not lap the sleeve 38 at all, or at least not until the annulus 36 is in registry with the annulus 88, and as a consequence no fuel would be injected into the engine; however, if desired a stop may be provided to limit movement of plate 46 and sleeve 38 to the right to thereby determine the minimum effective stroke of the plungers 24. Thus by varying the position of sleeve 38 the effective pumping capacity of the pump may be varied from zero or any desired minimum value to the maximum capacity of the pump.

In order to eliminate variations in the quantity of fuel pumped by the individual plungers resulting from variations in the relative locations of the annuli 34, 36 and 88, and variations in the diameters of the plungers which may occur during manufacturing of same, each of the by-pass sleeves 38 is adjustable relative to the plate 46. The adjustment of the sleeves in accordance with the present invention is extremely accurate, and minute adjustments may be effected.

Bearing in mind that, one of the members 38, 44 has one more notch than the other, as illustrated, it is possible to adjust each of the sleeves 38 laterally relative to the plate 46 in increments equal to the pitch of the thread on member 38 divided by the product of the number of notches on said members 38 and 44. Thus, for example,

if there are six notches on one member and seven on the other and the pitch of the thread is one thirty-second of an inch, the available increment of adjustment is the product of one thirty-second times one forty-second, or approximately seven ten-thousandths of an inch. To effect the smallest increment of adjustment available one portion of the bent end section 58 of spring 54, as for example, the curved portion 60, is moved out of the respective notch 52 in which it may be positioned by compressing spring 54, and the sleeve 44 rotated relative to the member 40 and the spring until said portion 60 of the spring engages the next adjacent notch 52. This effects an adjustment of one seventh of a revolution. Then the other or free end portion of the section 58 of the spring is lifted up and so moved out of engagement with the notch 42 in which it is received and the sleeve 44 and spring rotated together in the reverse direction until said free end engages the next adjacent notch 42 of member 40. This effects an adjustment in the opposite direction of one-sixth of a revolution and as a consequence the net adjustment is equivalent to the difference between one-sixth and one-seventh, or one forty-second of a revolution. Thus it will be apparent that extremely fine adjustments may be made with the present invention. However, while the number of notches in the respective parts of a sleeve assembly have been given as six and seven it is to be understood that any other suitable number of notches may be used in the respective parts, as heretofore set forth, it being understood that the notches of each member, if greater than one, are equally spaced relative to their respective members. It is to be further understood that while in the present example one part has one more notch than the other said part may have two or three more notches than said other or any other number that may be desired in connection with any particular installation. Obviously, the thread may be of any desired pitch.

It is thought that the invention and many of its attendant advantages will be understood from the foregoing description and though said invention has been illustrated in connection with but one modification thereof it will be apparent that various changes may be made in the form, construction and arrangement of the parts without departing from the spirit and scope of the invention or sacrificing all of its material advantages, the form hereinbefore described being merely a preferred embodiment.

I claim:

1. In an adjusting device: a pair of members having a screw thread connection and being adjustable relative to each other; locking means comprising a coiled spring carried on at least one of said members and having a longitudinally extending end portion; a plurality of circumferentially equally spaced recesses on one member engageable with the end portion; and a plurality of circumferentially equally spaced recesses on the other member also engageable with the end portion, there being a different number of said equally spaced means on one member than on the other member, said longitudinal portion of the locking means being longitudinally movable.

2. In an adjusting device: an externally threaded part; an annular flange on said part, a plurality of equally spaced notches disposed about the periphery of said flange; a member threadably received on the part; an annular flange on said member of substantially the same diameter

as the flange on the part; a plurality of notches in the flange of the member equally spaced about the periphery thereof; and spring latching means having a portion movable longitudinally relative to the device and slidably engageable with the notches of said part and said member.

3. The invention defined by claim 2 wherein the spring is coiled about the part between its flange and the member and said spring portion includes a curved section; the free end of the end portion being adapted to engage the notches of one flange and the curved section being adapted to engage the notches of the other flange.

4. In an adjusting device: an externally threaded sleeve part; an annular flange adjacent one end of the sleeve; a plurality of notches equally spaced about the periphery of the flange; an annular groove in the inner face of the flange; an annularly grooved part threadably received on the sleeve; a reduced end portion of the second mentioned part extending toward the flange on the sleeve; a plurality of notches in the second mentioned part adjacent the reduced end portion, said notches being equally spaced about the periphery thereof, there being a different number of notches in said second mentioned part than in the flange of the sleeve part; a spring coiled about the sleeve and reduced end portion and having the coiled ends received in the grooves in the flange and adjacent end of the second mentioned part and having a bent end section extending longitudinally relative to the axis of the parts, there being an outwardly curved portion in said longitudinally extending end section of the spring, a portion of the free end of said longitudinally extending end section being adapted to be received in the notches of one of the parts and the outwardly curved portion of said spring being adapted to be received in the notches of the other part.

5. In an adjusting device: a pair of members having a screw threaded connection and being adjustable relative to each other; a spring carried by the device and having a longitudinally extending end portion; a plurality of circumferentially equally spaced recesses on one member engageable by the end portion; and a plurality of circumferentially spaced recesses on the other member also engageable by said end portion; said end portion of the spring being operably movable longitudinally.

6. In an adjusting device: a pair of threadably connected members movable relative to each other; an annular flange on one of said members having a plurality of equally shaped notches about the periphery thereof; an annular ring on the other member having a flange extending toward the first mentioned flange and having a plurality of equally spaced notches therein; a spring coiled about the device between the flanges and having longitudinally extending end portion including a bent section adjacent one end adapted to be received in the notches of the second mentioned flange, the other end of said end portion being adapted to be slidably received in the notches of the first flange.

7. In an adjusting device: a pair of threadably connected members movable relative to each other; an annular flange on one of said members; an annular flange on the other member spaced laterally from same; a plurality of notches substantially equally spaced about the flanges; and locking means so constructed and arranged as to engage notches in the respective flanges for maintaining the members against movement relative

to each other, said locking means also being adapted to be slidably moveable into a released position for permitting adjustment of the members relative to each other.

8. In a fuel pump supplying fuel to an engine comprising a housing; a pumping plunger within the housing; a port in said plunger; a fuel passage leading from said port; a by-pass sleeve slidable on the plunger, said sleeve being so positioned as to control the port and to vary the effective stroke of the plunger; a member carrying the sleeve; a support for the member; flanges on said sleeve and member; engageable means equally spaced on said flanges; there being a different number of said means for one flange than the other; and locking means engageable with the respective engageable means for preventing movement of the parts relative to each other.

9. In a fuel pump for supplying fuel to an engine comprising: a housing; a plurality of pumping plungers circularly arranged and spaced apart within the housing; an annular channel for each plunger; a passage in each plunger connected with the channel thereof; a bypass sleeve slid able on each plunger for controlling the respective annular channels and adapted to vary the effective stroke of the respective plunger; a member carrying the sleeve; a support for said members; flanges on said sleeve and member the circumferences of which are substantially the same; engageable means equally spaced about the periphery of the flanges, there being a different number of means for one flange than the other; and resilient locking means engageable with the

respective engageable means for preventing movement of the flanged parts relative to each other.

10. The invention defined by claim 9 wherein there is means in the housing adjacent each sleeve for providing access thereto for adjustment thereof.

11. In a fuel pump for supplying fuel to an engine comprising: a housing; a plurality of pumping plungers circularly arranged and spaced apart within the housing; a fuel passage in each plunger; an annular channel in each plunger connected with the passage therein; a by-pass sleeve slid able on each plunger for controlling the annular channel thereof adjustable for varying the effective stroke of the plunger; a member carrying the sleeve; a scale for the sleeve having engageable means forming a part thereof and equally spaced apart thereon; a scale for the member of substantially the same length as the scale for the sleeve and having engageable means forming a part thereof equally spaced apart, the engageable means of one scale being spaced apart a greater distance than those of the other scale; resilient locking means disposed between the scales and cooperating with said engageable means for locking the sleeve and member together; an annular groove in the member; and a plate having peripheral notches circumferentially spaced apart in which the groove portions of the members are snugly but rotatably received, said members being held against lateral movement relative to the plate by the respective side walls of the groove.

GEORGE P. LUM.
